DETAILED DESCRIPTION

FIG. 1 is a schematic diagram of one form of apparatus for practicing the process of this invention.

FIG. 2 is a diagrammatic sectional elevation of the separator used in the apparatus of FIG. 1.

Referring to FIG. 1, a liquid containing blood solids is forced by pump 1 through pipe 2. Steam is injected through standard 45° pipe fittings 3 into the pipe to heat the liquid to the desired temperature. A temperature of 220-260° F. is usually maintained in the pipe downstream from the steam injectors.

The desired pressure is maintained in the pipe downstream from the steam injectors by an automatic, air operated back pressure valve 4. Typically, the pressure in this section is 15-45 p.s.i.g.

The back pressure valve is placed far enough downstream from the steam injectors to maintain the liquid at the elevated temperature and pressure for the desired period. Typically, this period is 10-20 seconds, but shorter or longer periods may be employed.

The liquid flows through the back pressure valve 4 to a scroll type centrifugal decanter 5. As shown in FIG. 2, the decanter has a conical bowl 6 and a scroll 7 coaxial with and inside the bowl 6. A helical screw 8 around the periphery of scroll 7 just clears the inside of bowl 6. The scroll 7 and bowl 6 are rotated in the same direction by a motor (not shown). The scroll rotates at a slightly higher speed than the bowl.

The liquid enters the decanter through a hollow center shaft 9 and is accelerated by the spinning scroll 7 and bowl 6 to the rotating speed of the bowl. Centrifugal action forces the heavier coagulated solids 10 against the sides of the bowl, while the remaining liquid forms a supernatant layer 11 above them.

The blood solids 10 are conveyed by the helical screw 8 on scroll 7 to the small end of the conical bowl 6 and ejected through a discharge chute 12. The solids leaving the chute 12 are in the form of small wet flakes which are much easier to handle than the powders produced by prior art processes. These flakes are dried in a rotary drum drier (not shown) and collected in a cyclone (not shown). The solids discharged from the cyclone are still in the flake form.

While the wet blood solids 10 are being carried out of the decanter by scroll 7, the remaining liquid 11 collects in the larger end of bowl 6, where it overflows a regulating ring 13, and enters a pumping chamber 14 where its kinetic energy is converted to pressure which forces it out of the decanter through line 15.

Of course, many modifications may be made to this system. The foregoing description and the following examples are merely illustrative and are not intended to limit the scope of this invention.

EXAMPLE I

Diluted whole beef blood was pumped through a one inch pipe at a rate of 1.75 gallons per minute and a pressure of 30-35 p.s.i.g. The temperature in the pipe was maintained at 230-235° F. by steam injection. The blood was discharged through a back pressure valve, located eight feet downstream from the last steam injector, into a scroll type centrifugal decanter with an inside bowl diameter of nine inches and a bowl length of 17 inches. The bowl speed was 5400 r.p.m. and the scroll speed was 5448 r.p.m. 37.8% of the diluted whole blood was collected as wet blood solids containing 40% moisture by weight. The liquid discharged from the decanter contained an average of 2.5% solids.

EXAMPLE II

Another test was conducted using beef blood which had been diluted by adding 30% by weight of water and operating the system described in Example I at a flow rate of 2 g.p.m., a temperature of 220° F., a pressure of 22-35

75

p.s.i.g., a decanter bowl speed of 3000 r.p.m. and a decanter scroll speed of 3020 r.p.m. 37.1% of the original diluted blood was collected as blood solids containing 64.2% moisture. The liquid effluent from the decanter contained an average of 3.8% solids.

EXAMPLE III

A third test with beef blood, again 30% diluted by the addition of water, was run on the same system at a flow rate of 2 g.p.m., a temperature of 230-240° F., a pressure of 20-30 p.s.i.g., a decanter bowl speed of 3000 r.p.m. and a decanter scroll speed of 3020 r.p.m. The liquid effluent from the decanter contained an average of 2.6% solids. 33.4% of the original diluted blood was collected as blood solids containing 56.2% moisture.

EXAMPLE IV

A diluted mixture of beef, hog and lamb blood was pumped at a rate of 9000 lbs. per hour and a pressure of 20 p.s.i.g. through a 2 inch pipe. Steam was injected into the line to heat the mixture to a temperature of 245° F. The back pressure valve was located 24 feet from the last steam injector.

The coagulated blood solids were extracted by scroll type centrifugal decanters operating at a bowl speed of 2100 r.p.m. and a scroll speed of 2115 r.p.m. The liquid effluent from the decanters contained an average of 1.2% solids.

EXAMPLE V

The system used in Example IV was operated at the same temperature, pressure, bowl speed and scroll speed but with a diluted blood flow rate of 6000 lbs. per hour. The liquid effluent from the decanters contained an average of 0.9% solids.

I claim:

1. A continuous process for separating blood solids from a liquid comprising:
  - (a) passing the liquid under pressure into a pressure vessel, said pressure being above the vapor pressure at the temperature to which the liquid is heated;
  - (b) heating the liquid by steam injection to a temperature above about 190° F. but below its boiling point while maintaining the liquid under pressure;
  - (c) retaining the heated liquid under pressure in the vessel for a period of at least five seconds, whereby the blood solids are coagulated under pressure; and
  - (d) discharging the liquid through a pressure reducer to a separator wherein the coagulated blood solids are extracted from the liquid.
2. A process according to claim 1 wherein the liquid in the vessel is at a pressure of 15-45 p.s.i.g.
3. A process according to claim 1 wherein the liquid is heated to a temperature of 220-260° F.
4. A process according to claim 1 wherein the heated liquid is retained in the vessel for 10-20 seconds.
5. A continuous process for separating blood solids from a liquid comprising:
  - (a) pumping the liquid through a pipe under a pressure above the vapor pressure at the temperature to which the liquid is heated, and heating the liquid by steam injection to a temperature above about 190° F. but below its boiling point while maintaining the liquid under pressure;
  - (b) retaining the heated liquid under pressure in the pipe for a period of at least about five seconds, whereby the blood solids are coagulated under pressure; and
  - (c) discharging the liquid through a back pressure valve to a scroll type centrifugal decanter wherein the coagulated blood solids are extracted from the liquid.
6. A process according to claim 5 wherein the liquid is pumped through the pipe at a pressure of 15-45 p.s.i.g.
7. A process according to claim 5 wherein the liquid is heated to a temperature of 220-260° F.

8. A process according to claim 5 wherein the heated liquid is retained under pressure in the pipe for 10-20 seconds.

9. A continuous process for coagulating and extracting blood solids from a liquid comprising:

(a) pumping the liquid at a pressure of 15-45 p.s.i.g. through a pipe, said pressure being above the vapor pressure at the temperature to which the liquid is heated, and heating the liquid to a temperature in the range of 220-260° F. but below its boiling point while maintaining the liquid under pressure;

(b) retaining the heated liquid under pressure in the pipe for a period of 10-20 seconds, whereby the solids are coagulated under pressure; and

(c) discharging the liquid through an automatic back pressure valve to a scroll type centrifugal decanter wherein the coagulated solids are extracted from the liquid.
